Primary Examiner — Kevin K Rudzinski*Assistant Examiner* — Richard E Yenchesky(74) *Attorney, Agent, or Firm* — Banner & Witcoff, Ltd.(57) **CLAIM**

The ornamental design for a mop, as shown and described.

DESCRIPTION

1. Mop

1.1 : Perspective

1.2 : Left

1.3 : Right

1.4 : Front

1.5 : Back

1.6 : Enlarged top view

The broken lines immediately adjacent to the shaded area define the bounds of the claimed design and form no part thereof; the broken lines showing the remainder of the mop represent unclaimed subject matter and form no part of the claimed design.

1 Claim, 6 Drawing Sheets(56)
